UNITED STATES PATENT OFFICE.

WILLIAM S. G. BAKER, OF BALTIMORE, MARYLAND.

CAR-TRUCK.

SPECIFICATION forming part of Letters Patent No. 415,892, dated November 26, 1889.

Application filed May 22, 1889. Serial No. 311,653. (No model.)

To all whom it may concern:

Be it known that I, WILLIAM S. G. BAKER, a citizen of the United States, residing at Baltimore, in the State of Maryland, have invented certain new and useful Improvements 5 in Car-Trucks, of which the following is a specification.

My invention more especially relates to the organization of electric-railway, car-trucks 10 and the trucks of cable-cars. In both of these classes of car-trucks it is usual to provide frames below the plane of the axles on which the electric motor or the grip mechanism is mounted. In the former class of trucks it is 15 desirable to have the entire space under the car as free as possible from obstructions, so that the electric motor and its accompanying mechanism may be properly mounted, and in the latter class it is necessary to have a 20 clear space at the center of the truck to accommodate the grip mechanism.

My invention consists in an improved organization of the brake mechanism of the trucks, whereby the brake-shoes are mounted 25 and operated without interference with the grip mechanism or the electric-motor mechanism.

In carrying out my invention I suspend the side beams of the depending frame from the 30 axle-boxes, preferably, in the manner shown and described in my patent, No. 399,468, of March 12, 1889. The brake-shoes are mounted directly on the side beams, and the brake- 35 shoe-operating mechanism is supported there- by. The cross-connecting beams of the de- pending frame heretofore used for supporting the brake-shoes are dispensed with.

In my improved truck as designed for grip- 40 cars rock-shafts on each side of the center of the truck are connected with the brake-shoes and are controlled by an operating-lever, whereby all the brakes may be simultane- 45 ously applied.

My truck as adapted for electric-motor cars 45 has the side beams connected by cross-beams near the center of the truck, and a central rock-shaft is provided, which is connected with and operates the several brake-shoes.

The details of construction and the subject- 50 matter claimed will be hereinafter designated.

The accompanying drawings show so much

of an electric-motor-car truck and a cable-car truck embodying all my present improvements in the best way known to me as is necessary to illustrate the subject-matter herein claimed.

Figure 1 represents a side elevation, and Fig. 2 a plan, of one side of a truck especially constructed for electric-motor cars. Fig. 3 is 6c a side elevation of part of a car-truck adapted for cable-cars. Fig. 4 is a plan view of the same, and Fig. 5 is a side elevation of a modified form of truck adapted for use in electric-motor cars.

The truck represented in Figs. 1 and 2 is shown as organized as follows: Axle-boxes A are arranged in pedestals B, similar in details of organization to corresponding parts shown in Letters Patent No. 354,964, granted 70 to me December 23, 1886, and No. 399,468, of March 12, 1889. These pedestals are bolted to the car-sills C and strengthened by braces D, as-usual. The side beams E of the depending frame are secured to the lower ends of 75 brackets or down-hangers F, extending over the axle-boxes, as shown in my patent last above mentioned, and a removable bolt H connects the lower ends of the pedestal-arms to permit of the ready insertion or removal of the 80 axle-boxes, wheels, and axles, as explained in said patent. Cross-beams J J', secured to the side beams E, may support the inner ends of the motors.

Brakes applied to the inner side of each 85 wheel are shown as consisting of brake-shoes L, of bell-crank form, connected by a central pivot l with a lever L', in turn working on a central pivot l' in a bracket L³ on the side beam E. The horizontal arm L² of the shoe 90 has one end of a coil-spring L⁴ secured to it, the other end being pivoted in the bracket L³, above mentioned. As the distance between the points of attachment of this spring to the bracket and shoe is equal to that between 95 the pivots of the rocking lever, the well-known "parallel motion" results, and the shoe is always pressed directly or in a right line against the wheel, thus insuring full contact and accurate bearing. The lower ends 100 of the rocking levers on each side are connected by a rope or chain m, provided with a tightening-link m' of well-known construction to regulate the tension of the chain,

which passes under pulleys or sheaves M M' on the side beams and over an intermediate sheave n, connected by a stirrup-link n' with a crank-arm n² on a rock-shaft N, mounted 5 on the side beams and extending across the frame between the cross-beams J J'. A lever N' on this rock-shaft may be connected by a chain n³ with a hand-wheel, as usual. This organization, it will be observed, dispenses 10 with the usual brake-beams and horizontal levers, which would be in the way of the motor, the only parts of the frame and brake mechanism extending across the truck between the axles being the cross-beams J J' 15 and the rock-shaft N; but these are so arranged as to be out of the way of the motors, which may be arranged in the usual way.

The truck shown in Figs. 3 and 4 is designed for cable cars. The side beams E are 20 provided at each end with brackets F, and may be suspended from the axle-boxes, as shown in Fig. 1. The cross-beams shown in my patent, No. 399,468, of March 12, 1889, are dispensed with, and the brake-shoes L are 25 supported on the side beams by means of brackets P and Q. The central bracket Q is preferably constructed with arms or flanges q, which embrace the beam E, and with a top portion Q', extending above the beam E on 30 its inner side. Upwardly-projecting arms q' are formed on the extension Q', which are perforated to receive the ends of the horizontal brake-guiding rods R. The rods R are rigidly secured at their inner ends to the 35 brake-shoes L, and their opposite ends extend through the arms q'. The ends of the rods are provided with nuts r, between which and the arms q' are interposed coiled springs r', which normally withdraw the brake-shoes 40 from the wheels. The brackets P are provided with flanges p, which embrace the beam E, and are formed with journal-boxes P' for the rock-shafts S.

It will be understood that Fig. 4 shows a 45 plan view of only one side of the truck, the other side being a duplicate of that shown. The brake-shoes are pivoted to links T, which are keyed to the rock-shafts S. The frame or housing U for the grip mechanism may be 50 of any usual construction. A short rock-shaft N is journaled in the bracket Q at u and in the grip-frame at u', and is provided with an operating-lever N', which may be connected with a hand-wheel, if desired. Downwardly-projecting arms L' are rigidly secured to the 55 rock-shafts S on one side of the space for the grip mechanism and are connected by chains or cables m, which extend over sheaves M M', and a central sheave n, which is connected 60 by a link n' with the arm n² of the lever N'. This organization of brake-operating mechanism is similar to that shown in Figs. 1 and 2, and it will be understood that when the sheave n is lifted the chain or cable m is 65 tightened, so as to rock the shafts S and apply the brake-shoes L to the wheels. The sheaves M, M', and n are mounted in a brack-

et V, secured to the grip-frame near the middle of the truck.

In Fig. 5 the side beam E is shown as provided with brackets F, as in the other figures, and the brake-shoes L are provided with guide-rods R, as in Figs. 3 and 4. The central bracket Q is, however, slightly modified, being secured to the cross-beams J J' and 75 made arch-shaped. One end of the rock-shaft N is shown as having its bearings in a box N², formed on the bracket, and the opposite end is similarly journaled on the opposite side of the truck. (Not shown.) The chains 80 or cables m, sheaves M, M', and n, lever N', and link n' are arranged and operated as in the other figures of the drawings.

It will be noted that in every instance the 85 brakes are supported by the side beams, and I have shown how the truck may be modified for electric and cable cars.

An important feature of the invention is the facility with which the wheels and motors may be removed. By simply removing 90 the bolts H the wheels and axles may be slipped out of the pedestals without in any way disturbing the brake mechanism, and the motors may be removed with the axles in the usual way. In other car-trucks of this 95 class it is necessary to disarrange the brake mechanism and take apart the frame in order to remove the wheels and motors.

Having thus fully described the construction and organization of my improved car-truck and car-brake, what I claim therein as new, and desire to secure by Letters Patent, is—

1. The combination, substantially as hereinbefore set forth, of the side beams and 105 wheel-brakes, each mounted independently on the side beams.

2. The combination, substantially as hereinbefore set forth, of the wheels, the side beams, the brake-shoes mounted on the side 110 beams, and the springs mounted on the side beams for normally withdrawing the brake-shoes from the wheels.

3. The combination, substantially as hereinbefore set forth, of the side beams, the 115 brake-shoes mounted on the side beams, and the brake-operating mechanism supported on the side beams.

4. The combination, substantially as hereinbefore set forth, of the wheel-brakes and a 120 separate rocking lever for each brake pivoted on the side beams of a car-truck.

5. The combination, substantially as hereinbefore set forth, of the wheel-brakes, the rocking levers on each of which its respective 125 wheel-brake is separately pivoted, the rocking-lever pivots on the side beams, and the springs intermediate of the side beam and brake-shoe.

6. The combination, substantially as hereinbefore set forth, of a brake-shoe, its central pivot on an arm in turn rocking on a pivot intermediate of its length on a side beam of the truck, and a spring pivoted at one end on

the side beam and at the other on an arm of the brake-shoe, thus constituting a parallel motion to insure a direct thrust of the brake-shoe on the wheel.

5 7. The combination, substantially as hereinbefore set forth, of a brake-shoe pivoted on a rocking arm in turn pivoted on the truck-frame, a spring-support for the brake-shoe, a rope or chain traversing a sheave on the frame and connecting this rocking lever with a crank-arm on a rock-shaft, a lever on this rock-shaft, and flexible connections between this lever and a hand-wheel to actuate the brake.

15 8. The combination, substantially as hereinbefore set forth, of brake-shoes pivoted on levers in turn rocking on the side beams of a truck-frame, sheaves on these side beams, a rope or chain connecting the brake-shoe 20 levers and traversing the sheaves, an interposed sheave suspended from a crank-arm on a cross-shaft, and a lever on the cross-shaft, thus actuating both shoes simultaneously without the use of central levers and 25 rods.

9. The combination, substantially as hereinbefore set forth, of a brake-shoe for each wheel, corresponding brake-shoe levers pivoted on the truck-frame, ropes or chains connecting the brake-shoe levers on the same side of the truck, sheaves on the side beams traversed by these ropes, a cross-shaft rocking in bearings on the side beams, its crank-arms, sheaves carried thereby interposed between the fixed sheaves, and an actuating-lever on the rock-shaft and between it and a hand-wheel, whereby all the brakes can be actuated by a single lever and yet have the center space of the truck unobstructed.

35 10. The combination, substantially as hereinbefore set forth, of car-axle boxes, down-hangers resting thereon, side beams supported by the brackets, central cross-beams

45 connecting the side beams, brackets on the side beams, brake-shoes pivoted thereon, a rope or chain connecting the brake-shoes on each side and traversing sheaves on the side beams, a rock-shaft mounted on the side beams between its cross-beams, crank-arms on each end of the rock-shaft, sheaves carried thereby acting on the brake-ropes, a lever on the rock-shaft and near one end thereof, and flexible connections between the lever and its actuating hand-wheel, whereby the 50 brakes can be actuated by a single lever, the 55 centerspace of the truck remain unobstructed, and the wheels readily may be removed or replaced.

11. The combination, substantially as hereinbefore set forth, of the wheels, the side 60 beams, the brake-shoes, the bracket Q, the horizontal guide-rods, and the springs on the ends of the guide-rods for normally holding the brake-shoes away from the wheels.

12. The combination, substantially as hereinbefore set forth, of the side beams, the 65 brake-shoes, the rock-shafts supported on the side beams beneath the brake-shoes, the downwardly-projecting arms or levers connecting the brake-shoes to the rock-shafts, and brake- 70 operating mechanism connected to the rock-shafts.

13. The combination, substantially as hereinbefore set forth, of the brake-shoes, the stationary sheaves M M', the movable sheaves 75 n, flexible connections between the sheaves and the brake-shoes, and a rock-shaft having an operating-lever and connected with the sheave n to raise and lower it.

In testimony whereof I have hereunto subscribed my name.

WILLIAM S. G. BAKER.
